UNITED STATES PATENT OFFICE.

WILLIAM AHLEN, OF DUQUESNE, PENNSYLVANIA.

GAGE-LOCKING DEVICE.

1,090,809.

Specification of Letters Patent. Patented Mar. 17, 1914.

Application filed September 4, 1913. Serial No. 788,145.

To all whom it may concern:

Be it known that I, WILLIAM AHLEN, a subject of the King of Sweden, residing at Duquesne, in the county of Allegheny and 5 State of Pennsylvania, have invented a new and useful Gage-Locking Device, of which the following is a specification.

My invention relates to the construction and arrangement of means employed in locking the sliding carriage, forming the stop or gage of metal cutting shears, in position on the gage bar or arm of the shear upon which the stop is adjustably mounted.

One object of my invention is to provide 15 a shear locking mechanism including means whereby the stop is moved away from, in front of the bars or other material being sheared and having novel means for adjusting the shear stop with relation to the shear 20 knives and for locking the adjustable stop in the various positions into which it is moved.

Referring to the drawings forming part 25 of this specification Figure 1 is a longitudinal side elevation showing a shear stop constructed and arranged in accordance with my invention. Fig. 2 is a partial plan on an enlarged scale showing in detail the locking device forming part of this invention. Fig. 30 3 is a side elevation of the apparatus shown in Fig. 2. Fig. 4 is an end elevation of the apparatus of Figs. 2 and 3 showing the ratchet wheel and pawl by which the worm forming part of my improved locking device 35 is held in adjusted position. Fig. 5 is a sectional end elevation showing the ratchet wheel and pawl by which the locking device is held in locking position. Fig. 6 is a detail elevation showing diagrammatically the 40 rotary movements of the eccentrically mounted worm forming part of my improved gage locking mechanism.

In the accompanying drawings the numeral 2 designates a horizontally extending 45 arm or gage bar forming a support for the adjustable sliding carriage 3 which is suspended therefrom so as to move lengthwise on the gage bar 2. The gage bar 2 is positioned to extend lengthwise at the rear 50 or on the discharge side of a metal cutting shear (not shown) above a feed table on which the sheared materials are conveyed away from the shear, the lower surface of the gage bar being provided with a series of

rack teeth for a purpose hereinafter described.

Pivots secured to one end of the sliding carriage 3 is a swinging stop 4 having a stop plate 5 thereon extending across the width of the stop to engage, when in operative position, with the end of the rods or other metal material being cut by the shears. The stop 4 is pivotally connected to one end of the link 6 which, with the link 7 to which it is pivotally connected, forms a toggle for moving the stop into and out of its operative position beneath the sliding carriage 3 on the gage bar 2. The link 7 is keyed or otherwise fastened to the pivot pin or shaft 8 on the rear end of the sliding carriage 3 and an operating lever 9 having a handle on its upper end is pivoted to one end of the shaft 8 for the purpose of operating the toggle links 6 and 7 in moving the stop 4 into and out of its operative position.

The toggle links 6 and 7 are arranged to be moved by the manually operated lever 9 and shift the stop 4 into and out of the operative position shown by full lines in Fig. 1 into and out of its disengaged or inoperative position, shown by dotted lines in this figure, so that the stop will clear the end of the materials when it is desired to deliver the sheared materials from the shear to a place of use or storage.

A rod 10 is pivoted at one end to the rear of the sliding carriage 3 and its opposite end projects through a slot in the flange 11 forming part of the stop 4. A helical spring 12, which is threaded on the rod 10, is employed to exert pressure on the flange 11 and hold the stop 4 in its raised or disengaged position as is indicated in dotted lines in Fig. 2 when the stop is raised by the hand lever 9. A similar rod 13 is pivoted at one end to the lever 9 and the opposite end of the rod 13 projects through a slot in the flange member 11 in the slot 4 in the same manner as has been described. A helical spring 14 is provided on the rod 13 which acts on the lever 9 so as to assist the spring 12 in holding the stop in its raised or disengaged position.

Pivots secured in openings on the front end of the sliding carriage 3 is a shaft 15 having a spur pinion 16 thereon, the teeth of this pinion engaging with the rack teeth in the under surface of the gage bar 2, and

a hand wheel 17 is secured on one end of the shaft 15 to provide means for manually adjusting the carriage 3 on the bar or arm 2 to bring the face of the stop plate 5 on the stop 4 the desired distance away from the face of the shear knives of the shear.

The apparatus as above described is old and does not in itself form part of this invention.

Pivoted on a bracket 18 which is provided on the rear end of the carriage 3, preferably with its longitudinal axis at an angle to the length of the carriage, is an eccentric shaft 19 and mounted so as to be rotatable on this shaft is a worm or screw 20, which is confined as to longitudinal motion relative to the carriage by the abutting bearings at its ends. The rear end of the eccentric shaft 19 is squared and has a ratchet wheel 21 thereon, the teeth of this ratchet engaging with the pawl 22 which is pivoted by one end to the shaft bearing on the bracket 18, the ratchet wheel and pawl being employed to hold the eccentric shaft 19 in its raised position in which the carriage is held against longitudinal movement on the gage bar 2. On one end of the worm 20, and secured to rotate therewith, is a second ratchet wheel 23 arranged to engage with the ratchet pawl 24 which is pivotally secured to the rear end of the sliding carriage 3, this ratchet wheel and pawl being employed to hold the worm or screw 20 in the position upon the shaft 19 into which it is turned to lock the carriage 35 on the bar 2 at a fixed distance from the shear blades. Holes 25 and 26 in the ratchet wheel 21 and in the worm 20 are provided to supply means for turning the worm 20 on the shaft 19 and for turning the eccentric shaft 19 in its bearings.

In the operation of my improved gage locking device the carriage 3 is moved lengthwise on the gage bar or arm 2 by means of the hand wheel 17 until the stop plate 5 on the stop 4 is at the necessary distance from the knives of the shear to cut the materials to the required length. The eccentric shaft 19 is then turned, preferably by means of a bar which is inserted in the holes 50 25 in the ratchet wheel 21, this movement of the eccentric shaft lifting the shaft and the worm 20 thereon until the tooth of the worm is raised from the depressed position shown in Fig. 6 into the raised position also shown 55 in this figure. At the time of lifting the worm 20 it, in the majority of instances, has to be rotated on the eccentric in order to make its thread mesh the spaces between teeth of the rack, after which it is locked by 60 engagement of the pawl 24 with the ratchet wheel 23. When in raised position the tooth of the worm 20 engages with one or more of the rack teeth in the gage bar 2 and, when the pawl 22 is thrown into operative engagement with the teeth of the ratchet wheel, the

worm will be held in such position until the pawl has been disengaged and the shaft 19 is turned in the reverse direction to again bring the worm into its depressed or disengaged position. The material being sheared 70 is then fed forwardly between the knives of the shear until the end or ends thereof strike against the stop plate 5 on the stop 4, the stop being positioned as shown in full lines in Fig. 1. The shear is then actuated to 75 sever the portion of the material in engagement with the stop 5 from the remainder of the multiple length materials. The materials then rest upon the delivery feed table, but endwise movement thereof away from 80 the shear is prevented by reason of the stop plate 5. The lever 9 is then moved manually from the position shown in full lines into that shown by dotted lines in Fig. 1, and this movement of the operating lever 9 raises 85 the toggle links 6 and 7 from the full line position of Fig. 1 into that shown by dotted lines. This movement of the toggle raises the stop 4 and stop plate 5 so as to be above, and clear the sheared materials then resting 90 upon the feed table, and permit lengthwise travel thereof on the feed table away from the shear. The lever 9 is then swung to again lower the stop 4 and stop plate 5 into 95 operative position and the materials to be cut are again moved into engagement with the stop plate, when the shearing operation is again performed. The above described operations are then repeated as often as is necessary to cut the materials into the length 100 determined by the position in which the stop is then locked on the gage bar 2.

When necessary to cut materials to a different length the ratchet pawl 22 is released and the eccentric shaft 19 is turned to free 105 the worm from the rack teeth in the gage bar 2 (the position shown in dotted lines in Fig. 6). The hand wheel 17 is then manipulated to move the sliding carriage 3 on the gage bar 2 until the stop is at the desired 110 distance from the shear knives. The worm 20 is then again adjusted to bring it into locking engagement with the adjacent rack teeth in the gage bar 2 as has been described and the operations described are repeated. 115

The advantages of my invention will be apparent to those skilled in the art. By the use of the worm and eccentric shaft the gage lock is easily and quickly moved into and out of locking position and when moved into 120 locking position the worm forms a positive stop which prevents any movement of the gage or sliding carriage on the gage bar or arm.

Modifications in the construction and arrangement of the parts may be made without departing from my invention.

The construction of the sliding carriage and gage bar or arm may be changed; the means employed in actuating the stop plate 130

may be varied, and other changes may be made within the scope of the appended claims.

I claim:

5. 1. In a shear gage locking device, the combination with a horizontally extending gage bar having rack teeth in the lower surface thereof and a sliding carriage movable lengthwise on said bar, of means on 70 said carriage for locking the carriage on said bar, said means comprising a screw arranged to raise and lower into and out of engagement with the rack teeth on the bar, and means whereby said screw is moved 15 into and out of engagement with said rack teeth.
2. In a shear gage locking device, the combination with a horizontally extending gage bar having rack teeth in the lower surface 75 thereof and a sliding carriage movable lengthwise on said bar, of means on said carriage for locking the carriage on said bar, said means comprising a screw arranged to raise and lower into and out of engagement with the rack teeth on the bar, means whereby said screw is moved into and out of engagement with said rack teeth, and means for holding said screw in engagement with the rack teeth.
- 20 3. In a shear gage locking device, the combination with a horizontally extending gage bar having rack teeth in the lower surface thereof and a sliding carriage movable lengthwise on said bar, of means on said carriage for locking the carriage on said bar, said means comprising a screw arranged to engage said rack teeth to hold the carriage in adjusted position on said gage bar, a rotatable eccentric shaft on 90 which said screw is mounted, and means for holding said shaft to prevent disengagement of the screw and rack teeth.
4. In a shear gage locking device, the combination with a horizontally extending gage bar having rack teeth in the lower surface thereof and a sliding carriage movable lengthwise on said bar, of means on said carriage for locking the carriage on said bar, said means comprising a screw arranged to engage said rack teeth to hold the carriage in adjusted position on said gage bar, a rotatable eccentric shaft on which said screw is mounted, means on said shaft whereby the shaft is turned to move the screw into and out of engagement with the rack teeth, means for holding said shaft to prevent disengagement of the screw and rack teeth.
- 25 5. In a shear gage locking device, the combination with a horizontally extending gage bar having rack teeth in the lower surface thereof and a sliding carriage movable lengthwise on said bar, of means on said carriage for locking the carriage on said bar, said means comprising a screw arranged to engage said rack teeth to hold the carriage in adjusted position on said gage bar, a rotatable eccentric shaft on which said screw is mounted, means on said shaft whereby the shaft is turned to move the screw into and out of engagement with the rack teeth, means for holding said shaft to prevent disengagement of the screw and rack teeth, and means for holding the screw against rotation on said eccentric shaft.
6. In a shear gage locking device, the combination with a horizontally extending gage bar having rack teeth in the lower surface thereof and a sliding carriage movable lengthwise on said bar, of means on said carriage for locking the carriage on said bar, said means comprising a screw arranged to engage said rack teeth to hold the carriage in adjusted position on said gage bar, a rotatable eccentric shaft on which said screw is mounted, means on said shaft whereby the shaft is turned to move the screw into and out of engagement with the rack teeth, means for holding said shaft to prevent disengagement of the screw and rack teeth, and means for holding the screw against rotation on said eccentric shaft.
- 30 7. In a shear gage locking device, the combination with a horizontally extending gage bar having rack teeth in the lower surface thereof and a sliding carriage movable lengthwise on the gage bar, of a screw rotatably mounted on the carriage and arranged to swing eccentrically to move into 95 and out of engagement with the rack teeth, means for moving the screw eccentrically into and out of engaging position with the rack teeth, and means for rotating the screw to move the screw into contact with the rack teeth.
8. In a shear gage locking device, the combination with a horizontally extending gage bar having rack teeth in the lower surface thereof and a sliding carriage lengthwise movable on the gage bar, of a rotatable screw, an eccentric shaft on said carriage on which said screw is rotatably mounted arranged to move the screw into and out of engagement with the rack teeth, means for 105 turning the eccentric shaft to move the screw into and out of engagement with said rack teeth, and means for preventing rotation of the eccentric shaft to hold the screw in locking position.
9. In a shear gage locking device, the combination with a horizontally extending gage bar having rack teeth on its lower surface and a sliding carriage lengthwise movable on the gage bar, of a rotatable 110 screw, an eccentric shaft on the carriage, on which said screw is rotatably mounted, arranged to move the screw into and out of engagement with the rack teeth, means for turning the eccentric shaft, means whereby 115 said screw is turned on the eccentric shaft, and means for holding the eccentric shaft in turned position on said carriage.
10. In a shear gage locking device, the combination with a horizontally extending 120
- 35 40 45 50 55 60 65 70 75 80 85 90 95 100 105 110 115 120 125 130

gage bar having rack teeth on its lower surface and a sliding carriage lengthwise movable on the gage bar, of a rotatable screw, an eccentric shaft on the carriage, on which said screw is rotatably mounted, arranged to move the screw into and out of engagement with the rack teeth, means for turning the eccentric shaft, means whereby said screw is turned on the eccentric shaft, and

means for holding the eccentric shaft and 10 screw in turned position on said carriage.

In testimony whereof, I have hereunto set my hand.

WILLIAM AHLEN.
